DISPLAY CONTAINER

Chester J. Abend, Camillus, and William A. Morrison,
Solvay, N.Y., assignors to SCM Corporation, New York, N.Y., a corporation of New York

Filed May 10, 1965, Ser. No. 85,202

Term of patent 14 years

(Cl. D58—12.7)

We claim:

The ornamental design for a display container, substantially as shown and described.
